Inventor:

John B. Crofoot,
By Joshua A. Hoste
his Attorney.

Patented Oct. 16, 1928.

UNITED STATES PATENT OFFICE.

JOHN B. CROFOOT, OF ARLINGTON HEIGHTS, ILLINOIS.

MAGAZINE HAMMER.

Application filed August 26, 1926. Serial No. 131,580.

My invention relates to improvements in magazine hammers and has for its object the provision of an improved construction of this character by means of which fastening elements, such as staples, may be repeatedly and continuously applied and driven in position.

Other objects will appear hereinafter.

The invention consists in the combinations 10 and arrangements of parts hereinafter described and claimed.

The invention will be best understood by reference to the accompanying drawings forming a part of this specification, and in 15 which,

Fig. 1 is a side view of a magazine hammer embodying the invention;

Fig. 2 a top plan view thereof shown partially in horizontal section;

Fig. 3 a transverse section taken substantially on line 3—3 of Fig. 1;

Fig. 4 a vertical longitudinal section of the same.

The form of construction illustrated in 25 the drawings comprises a hammer head 20 in the form of an enclosing casing having a vertically reciprocating spring-held operating plunger 21 mounted therein as shown. The operating plunger 21 is provided with a cam surface 22 operating a reciprocating spring-held bolt 23 carrying a spring-held pawl 24 cooperating with a spring-held stop pawl 25 to cause automatic feeding, severing and driving of staples 30 from a staple strip 26. The construction for feeding, severing and driving the staples 35 from the staple strip 26 is a well-known mechanism for the purpose, being fully illustrated in my prior Patent, No. 1, 224,076, 40 and requires no further description here, the same constituting no part of the present invention except in so far as it cooperates with the parts to be presently described.

By holding the handle 34 in the hand and 45 striking a blow with the hammer head 20, a staple from the staple strip 26 will be automatically severed and driven by the action of the plunger 21. In this manner 50 the device may be employed as a magazine hammer for quickly, efficiently and positively driving the staples for securing light articles, such as address cards or the like in places on boxes. The specific form and

arrangement of parts hereinafter described constitutes a simple and effective one for the 55 purpose.

The form of construction illustrated constitutes a positive arrangement for operating the plunger 21. To this end the hammer head 20 is provided with a rigid operating 60 handle 34 for manipulating the same. A striking head 35 is slidably mounted on the head 20 in alinement with the plunger 21. Said striking head is mounted on a sleeve 36 which is slidable in the head 20 and has a guide passage 37 in which the plunger 21 slides and operates, the sleeve 36 receding into the head 20 when a blow is struck. The striking head 35 is connected at opposite 65 sides by links 38 with the lowermost joints 70 39 of toggle joint constructions 40 mounted on opposite sides of the head 20. The lateral joints 41 of said toggle joints are provided with rollers operating in slots 42 in head 20 whereby said toggle joints are nicely held 75 in place and guided during their operations. The upper joint 43 of each toggle joint is connected by a link 44 with a collar or head 45 on the upper end of the plunger 21. By this arrangement it will be noted that upon 80 striking a blow with the hammer head 20, the striking head 35 will recede into the head 20, thus causing positive operation of the plunger 21 to sever and drive a staple as before. It will be noted that this arrangement 85 exerts a positive, powerful and direct action upon the plunger 21, thus insuring operation thereof at each blow. The specific form and arrangement of parts is a simple and effective 90 one for the purpose.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A magazine hammer comprising a hammer head including a reciprocating plunger; 105 means in said head operable by reciprocation

of said plunger for applying and driving a fastening element; a handle rigidly secured to said head; a yielding striking member projecting from said head; and a toggle joint 5 connection between said striking member and said plunger for reciprocating the latter upon striking a blow, substantially as described.

2. A magazine hammer comprising a hammer head including a reciprocating spring-held plunger; means in said head operable by reciprocation of said plunger for applying and driving a fastening element; a handle rigidly secured to said head; a strik-

ing member projecting from said head in 15 alinement with said plunger, said striking member being provided with a sleeve slideable in said head and slideable over said plunger, said plunger operating through said striking member; and a toggle joint 20 arrangement at each side of said head operatively connected with said striking member and said plunger for reciprocating the latter upon striking a blow, substantially as described. 25

In testimony whereof I have signed my name to this specification.

JOHN B. CROFOOT.
